TELEGRAPH SIGNAL REGENERATING APPARATUS

Reginald Dennis Salmon, Croydon, England, assignor to Creed and Company Limited, Croydon, Surrey, England

Application September 24, 1930, Serial No. 484,075, and in Great Britain January 21, 1930

13 Claims. (Cl. 178—69.5)

This invention relates to signal regenerating apparatus in telegraphic systems in which changes of line current constituting the signals are originated at definite multiples of a unitary element of time.

In telegraphic systems of this class it is a great advantage to employ means capable of independent harmonic motion in signal receiving and reproducing apparatus and to synchronize this harmonic motion to that of the unitary elements of the signals. Suitable small portions of the received signals can be selected thereby at definite regular intervals to determine the character of reproduced signals, the timing and formation of the reproduced signals being determined by the regular harmonic motion of the said means.

This means may consist of a vibratory member such as a reed or tuning fork, but a more usual method is to employ a rotating shaft. The principle, however, is the same and essentially consists of means to effect operations at regular cyclic intervals. In this manner signals can be reproduced free from the distortion, attenuation and other irregularities attendant on transmission over a line.

The methods of synchronizing the harmonic motion of the signal regenerator to the received signals may consist of sending at regular spaced intervals a special synchronizing impulse from the transmitting apparatus, which is utilized to effect a correcting tendency on the harmonic motion of the regenerator to bring it into the desired phase relation with the received signals. Synchronization may also be effected through the medium of the received signals themselves. A telegraphic signal synchronizing apparatus of this latter class and in which the synchronized member consists of a rotating shaft is shown in British Patent No. 308,672. A telegraphic signal regenerating apparatus in which a rotating shaft synchronized with received signals is employed to select small portions of the received signals and to reproduce them in regenerated form is shown in British Patent 309,388.

A common feature of all these methods of signal synchronization and regeneration is that operations are required to be effected in accordance with the polarity or character of received signals at recurrent short intervals of time. The length of the interval of time required for an operation in one manner or another is determined by the polarity and character of the signal during that interval. The smaller this interval the greater will be the margin of tolerance.

In the case of a synchronizer, for example, the phase of the regenerator is constantly oscillating between lagging and leading relative to mean true synchronism with the received signals. At correct phase relation the correcting means tending to bring the phase of the regenerator into synchronism with the received signals is unaffected. It is necessary for the phase difference to exceed a certain amount in order to actuate this correcting means. The smaller this amount necessary the greater will be the degree of synchronization attainable. In the case of a signal reproducer it will be seen that the smaller the portion corresponding to the true mean centre of a received signal necessary to select the character of the reproduced signal, the greater will be the margin for distortion of received signals. This distortion as is known, is permissible on the boundaries of each signal element up to the limits of that middle portion reserved for selecting the reproduced signal element.

The apparatus shown in the specifications hereinbefore mentioned effects by mechanical means the operation of contact levers to one position or another by momentary actuation of abutment devices. To obtain the necessary duration of contact to effect the operation of means such as electromagnetic relays connected thereto, local holding means such as a spring pressed jockey roller riding on a knife edge formed on the contact lever is employed. The present invention permits a high speed of operation by electrical methods, in which means connected in the anode circuit of a thermionic valve effects each operation in accordance with the potential of the grid resulting from a charge communicated to the grid circuit during a very brief contact period.

The sustained effect on the anode current of a three electrode valve due to the charging of the grid circuit when sufficient capacity is associated with the grid circuit to maintain the grid at a potential which is substantially constant for a period following the charging of the grid circuit, is known. The present invention applies this principle to telegraphic regenerating apparatus in which operations are effected in accordance with the polarity or character of received signals only at definite brief intervals in a train of received signals, and is characterized in that means connected in the anode circuit of a thermionic valve effects each said operation in accordance with the potential of the grid resulting from a charge communicated to the grid circuit in each said brief interval of time. A feature of the pres-

ent invention therefore, consists of telegraphic synchronizing apparatus in which the essential elements comprise cyclic switch means locally timed and alternately selecting one of two potentials, switch means timed by received signals to charge the grid circuit of a thermionic valve in accordance with the selected potential, means responsive to change of anode current said thermionic valve consequent upon said charge of the grid circuit, and means operated thereby tending to adjust the local timing of said cyclic switch means to that of said received signals.

Another feature consists of telegraphic signal reproducing apparatus in which the essential elements comprise means responsive to received signals to select one of two potentials, cyclic switch means maintained in synchronism with received signals to charge the grid circuit of a thermionic valve in accordance with the selected potential in a brief interval corresponding to the mean centre of each received signal element, means responsive to change of anode current of said thermionic valve consequent upon said charge of the grid circuit, and means operated thereby to reproduce said received signals.

Another feature consists of employing a rotating shaft to effect cyclic switching operations for maintaining synchronism with received signals and for reproducing said received signals in regenerated form.

Another feature is that means is employed for adjusting the phase relation between cyclic switching operations for maintaining synchronism and cyclic switch operations for the reproducing signals in regenerated form. If a rotating synchronized shaft is employed for example, the cam members or the commutator switching members for the two switching operations respectively may be adjusted relatively on the shaft. Alternatively, one set of switching members or brushes, according to the means employed, which co-operate with the rotating shaft may be adjusted angularly while the other set remains fixed. By this means when synchronism is attained the middle portions of the received signals may be selected.

Another feature consists of incorporating a mechanical relay in telegraphic synchronizing and reproducing apparatus in which a rotating shaft is employed to effect cyclic switching operations, the mechanical relay effecting switching operations timed by and responsive to received signals.

Still another feature consists of employing insulating drums carrying suitable metal inserts and upon which drums are stationary brushes adapted to effect cyclic switching operations during the rotation of a shaft. Other features will be evident from the following descriptions when taken in conjunction with the accompanying drawing in which Fig. 1 represents diagrammatically and by way of example a telegraph signal regenerator in which both means for synchronizing and means for reproducing regenerated signals are arranged according to the present invention. Fig. 2 illustrates details of a rotary switching means for adjusting phase.

Referring to Fig. 1, a shaft 1 is driven through a variable speed gear comprising disc 2 and friction wheel 3, from a motor 4 which is under the control of one or the other of two speed governors 5 and 6. With a shunt wound motor as shown, governor 5 would be adjusted to govern the speed of the motor so that shaft 1 rotates about $\frac{1}{2}\%$ faster than true synchronous

speed of the incoming signal elements when under the control of this governor. Governor 6 would be likewise adjusted so that shaft 1 rotates about $\frac{1}{2}\%$ slower than true synchronous speed when under the control of this governor.

It will be noted that with the arrangement as shown of a shunt wound motor and governing by means of short circuiting a resistance in series with the field winding when the governed speed is exceeded, if both governors 5 and 6 are connected in parallel with this resistance the motor will be governed by governor 6 at the lower of the two speeds. If the circuit through governor 6 is broken the motor speed increases until the other governor 5 functions at the higher speed. Any convenient method, however, may be adopted for driving shaft 1 at one or other of two ground speeds: the precise arrangement forms no essential part of the present invention.

Shaft 1 actuates two circuit controlling devices represented in this case as commutators 7 and 8 consisting of two insulating drums each carrying a suitable inserted metal conductor and upon which drums stationary brushes 9-13 are arranged to bear. The inserted metal conductor in commutator 7 is so arranged that during one half revolution, brush 10 is electrically connected to brush 9 and insulated from brush 11: during the other half revolution brush 10 is connected to brush 11 and insulated from brush 10. Commutator 8 consists of an insulating drum carrying an axially arranged inserted metal bar 34 (see Fig. 2). The angular width of the metal bar and the corresponding angular bearing surfaces of the brushes 12 and 13 are made small so that a very brief interval of electrical connection is effected between brushes 12 and 13 at each revolution of the shaft 1. Contact springs actuated by suitably contoured cams may if desired replace the commutators as above described or any other forms of suitable circuit controlling devices actuated by shaft 1 may be substituted. The essential requirement in the first mentioned case is to effect a change over in connection from one circuit to another at each half revolution of shaft 1 and 2, in the second mentioned case a very brief interval of contact is made once in each revolution of shaft 1. In both cases, switching operations are effected, timed by the rotating shaft.

A mechanical relay 14 having two eccentrics 15, 16, which are 90° out of phase for actuating contact arms 17 and 18 respectively may conveniently, though not essentially, be driven from shaft 1. The escapement or clutch controlling member of the mechanical relay is actuated by the armature 20 of an electro-magnetic relay 19 which is responsive to received signals. At each actuation of the armature 20, the driven member of the clutch of the mechanical relay rotates half a revolution and eccentric 16 thus actuates contact lever 18 from one extreme position to another, to make contact with contact screw 21 and 22 according to whichever side armature 20 of relay 19 is actuated. At each actuation of armature 20 moreover, the second eccentric 15 of the mechanical relay actuates contact lever 17 to make momentary contact with one or the other of contact screws 23 and 24. This, as stated, is effected by eccentric 15 which is 90° out of phase with eccentric 16. It will be seen therefore that the normal position of rest of contact lever 17 is midway between contact screws 23 and 24, while the normal position of rest of contact lever 18 is against contact screw 150

21 or 22. The function of contact levers 17 and 18 actuated by the mechanical relay upon response of the electromagnetic relay 19 is to actuate circuit controlling devices at each change 5 in polarity or character of the line current constituting the received signals. The circuit controlling device 17 closes a circuit at periods determined by the instants at which the received signals change polarity or character, while the 10 circuit controlling device 18 relays the signals as received by relay 19. It is not essential that these operations be effected by a mechanical relay as shown: other methods may be adopted as will be apparent to those skilled in the art. The 15 essential feature is that switching operations are effected, timed by the signals as received.

Each of the two commutators 7 and 8 actuated by the shaft 1 is associated through contact levers 17 and 18 respectively with one of two 20 three electrode thermionic valves 25 and 26. A grid battery 27, opposite poles of which are connected to brushes 9 and 11 is joined by one pole, in this case from brush 11 to the grid of valve 25. Brush 10 is connected to contact lever 17, 25 and contact screws 23 and 24 are commoned and connected to the filament of this valve 25. A condenser 28 of a suitable value is connected between the grid and filament to give this grid circuit sufficient capacity for the purpose herein- 30 after mentioned. An electromagnetic relay 29 in the anode circuit of valve 25 is adapted to actuate its contact tongue from one side to the other in accordance with the variations of anode current supplied by the high tension battery 30. 35 The contact tongue of relay 29 alternately opens and closes the circuit through governor 6 of motor 4. Commutator 8 is somewhat similarly connected to valve 26. Brush 12 is connected to contact lever 18. One pole of a grid battery 31 40 is connected to contact screw 22 the other pole being connected to contact screw 21 and to the filament of valve 26. Brush 13 of commutator 8 is connected to the grid of valve 26 and a condenser 32 of a suitable value is connected in 45 this grid circuit. An electromagnetic relay 33 in the anode circuit actuates its contact tongue in accordance with the variations of anode current and repeats the regenerated signals to line as shown, or may be utilized to operate local 50 signal recording means.

The arrangements as described are purely schematic, the principle involved will be seen in either case to consist of charging the grid circuit of either valve to one of two potentials. 55 For the synchronizing valve 25 the potential is selected by commutator 7 and impressed when contact lever 17 makes contact with either of contact screws 23 and 24. For the signal regenerating valve 26, the potential is selected by contact lever 18 and impressed when commutator 8 makes momentary contact. The capacity of the grid circuit of each valve is adjusted by condensers 28 and 32 respectively so that the grid which in each case is charged to one or the other 60 potential in a very brief interval of time, maintains that potential substantially unchanged over an interval of time. This permits the corresponding electromagnetic relay in the anode circuit to be actuated to one side or the other 65 in accordance with the strength of the anode current when the grid is substantially at either of these two potentials.

The whole arrangement forms a device whereby the rotating shaft 1 is maintained in synchronism 70 with the incoming signals, the phase of the shaft

being determined by commutator 7, while commutator 8 is adjustable on shaft 1 relatively to commutator 7 so that the contact bar passes under the brushes 12 and 13 at the instant in each revolution of shaft 1 which corresponds to the true mean centre of each received signal element. If shaft 1 is in its exact synchronous position brushes 9, 10 and 11 will be momentarily connected together at the instant contact lever 17 touches contact screw 23 or 24 consequent upon the actuation of armature 20 to one side or the other in response to the character of a received signal. It will be noted that this instant is not necessarily the same instant at which the armature 20 is actuated, for the mechanical relay has a small but definite time lag. The effect is the same, however, as will be seen. If the shaft 1 is ahead of its correct position, one brush, 9 for example, will be connected to brush 10 at the instant contact lever 17 is actuated. The grid circuit of valve 25 is thereupon charged so that the grid is negative to the filament, the anode current is reduced and the armature of relay 29 joins governor 6 in circuit with motor 4 so that the speed of shaft 1 thereupon drops from $\frac{1}{2}\%$ above true 80 synchronous speed to $\frac{1}{2}\%$ below. The motor continues to be governed at the lower of the two speeds until the phase of shaft 1 has fallen behind its true synchronous positions. When this occurs brush 11, instead of brush 9 will be connected to brush 10 at the instant contact lever 17 is actuated. Then battery 27 applies no potential to the grid of tube 25. This potential, however, when compared to the former negative potential may be considered as a relatively positive potential. 85 Furthermore, in accordance with well-known or conventional tube circuits, a positive potential may be momentarily impressed on the grid of tube 25 from the positive terminal of the battery used to heat the filament of this tube. Since 90 100 condenser 28 is short circuited at the instant contact lever 17 is actuated the above circuits will then be completed and a corresponding potential will be applied to the grid of tube 25. This will result in an increase of the anode current and 105 a consequent actuation of the armature of relay 29 to its open position. This opens the circuit through governor 6 and the motor 4 is thereafter governed by the other governor 5 at the 110 lower of the two speeds. The phase of shaft 1 115 120 therefore picks up again and the action is such as to maintain this phase constantly oscillating slightly from lagging to leading and vice versa with respect to the signal periods as represented by the actuation of armature 20 of relay 19. 125

As already stated, the grid circuit of valve 26 is completed through brushes 12 and 13 at the instant which represents the true mean centre of the received signal element. The polarity to which the grid is charged is determined by the 130 position of contact lever 18 which has already been actuated to contact screw 21 or 22 according to the polarity or character of the signal. Relay 33 is thereafter actuated to one side or the other according to the strength of the anode current 135 and reproduces each signal element in regenerated form free of distortion.

What is claimed is:

1. In a telegraph system, synchronizing apparatus comprising means providing two different potentials, a thermionic valve, cyclic switch means locally timed and adapted alternately to select one and then the other of said potentials, switch means timed by received signals to charge the grid circuit of said thermionic valve in ac- 145

- cordance with the selected potential, relay means responsive to change of anode current consequent upon said charging of the grid circuit, said relay means being operatively associated with speed varying means for controlling the timing of said cyclic switch means in accordance with that of said received signals.
2. Telegraph synchronizing apparatus comprising a rotatable shaft, driving means therefore, switch means operated and timed by said rotatable shaft to select alternately one and then the other of two potentials, other switch means timed by and responsive to received signals to charge the grid circuit of a thermionic valve in accordance with the selected potential, relay means responsive to the change of anode current consequent upon said charging of the grid circuit, and speed governing means controlled thereby to maintain said rotatable shaft in synchronism with received signals.
3. Telegraph signal regenerating apparatus comprising a rotatable shaft, driving means therefore, switch means operated by said rotatable shaft to select alternately one and then the other of two potentials, other switch means operated by said rotatable shaft to close a circuit for brief intervals corresponding to the mean centres of received signal elements, signal responsive means, switching means operated thereby to close a circuit at brief intervals corresponding to the timing of changes in the character of the received signals, other switching means operated by said signal responsive means to select one or the other of two potentials in response to received signals, thermionic valve means controlled by said potentials, speed governing means controlled by said valve means to maintain said rotatable shaft in synchronism with the received signals and signal reproducing means also controlled by said valve means to reproduce the received signals in regenerated form.
4. In telegraph signal regenerating apparatus, a rotatable shaft, driving means therefore, switch means operated by said rotatable shaft to select alternately one and then the other of two potentials, speed governing means controlled thereby to maintain said rotatable shaft in synchronism with received signals, other switch means also operated by said rotatable shaft to close a circuit at brief intervals corresponding to the timing of the changes of character of the received signals, signal reproducing means controlled by the last mentioned switch means, and means to adjust the phase relation between the operation of the two switching means effected by said rotatable shaft.
5. In telegraph synchronizing apparatus, a rotatable shaft, driving means therefore, a speed governing device adjusted to effect rotation of said shaft at a speed slightly above true synchronous speed with received signals, a second speed governing device adjusted to effect rotation of said shaft at a speed slightly below true synchronous speed, a relay responsive to received signals, switch means operated by said shaft to select one or the other of two potentials at each response of said relay and means controlled thereby to render one or the other of said speed governing devices operative upon said driving means.
6. In telegraph synchronizing apparatus, a rotary shaft, a thermionic valve, switch means operated and timed thereby to select alternately, one and then the other of two potentials, other switch means operated under control of received signals by said rotary shaft to charge the grid circuit of said thermionic valve in accordance with the selected potential, relay means responsive to the change of anode current consequent upon said charging of the grid circuit and speed governing means controlled thereby to maintain said rotary shaft in synchronism with received signals.
7. In telegraph reproducing apparatus, a thermionic valve, an electromagnetic relay responsive to the character of received signals, a shaft rotating in synchronism with the received signal elements, a mechanical relay operated by said shaft under control of said electromagnetic relay to select one or the other of two potentials, switch means also operated by said shaft to close a circuit at brief intervals corresponding to the mean centre of each signal element, and thereby to apply the selected potential to said valve only during said brief intervals of time.
8. In combination, a rotary shaft, alternate switching means and circuit closing means operated thereby, signal responsive means, means yielingly driven by said shaft and controlled by said signal responsive means and circuit closing and alternate switching means operated thereby to maintain said shaft in synchronism with received signals and to reproduce said signals in regenerated form.
9. In signal regenerating apparatus, a rotary shaft, three stationary brushes, an insulating cylindrical drum associated therewith and carried by said shaft, commutating metal inserts in said cylinder to arrange and to connect said brushes alternately in pairs at each half revolution of said shaft, a second insulating cylindrical drum carried by said shaft, a narrow longitudinally extending metal insert therein, two brushes cooperating therewith to effect simultaneously a brief interval of contact and once in each revolution of said shaft, and means to adjust the period in which said brief interval of contact is made relatively to the period of connection in pairs of the three brushes aforesaid.
10. In signal regenerating apparatus a mechanical relay comprising means responsive to the character of received signals, an escapement actuated thereby, a rotatable member released for half a revolution at each actuation of said escapement, two eccentrics relatively displaced 90 degrees on said rotatable member, a contact tongue actuated by one eccentric from a mid position to make contact at the extreme positions, and a second contact tongue actuated by the second eccentric from one extreme position to the other at each said half revolution.
11. In a telegraph system, synchronizing apparatus comprising a relay responsive to receive signals, an escapement actuated thereby, a rotatable member releasable for half a revolution at each actuation of said relay, an eccentric carried by said rotatable member, a rotatable shaft having yielding driving engagement with said rotatable member, motor means for rotating said shaft approximately in synchronism with received signals, speed regulating means for said motor means having two alternative limiting speeds respectively above and below the synchronous speed, a thermionic valve, means providing two different potentials, a switch device carried by said rotatable shaft arranged to close alternate contacts during successive half revolutions to render said potentials alternately available for application to the grid circuit of said valve, switch means operatively connected with

5 said eccentric for momentarily closing said circuit during each half revolution thereof and relay means responsive to changes in the anode current of said valve and operatively associated with said speed regulating means to determine the effective limiting speed thereof.

12. In a signal regenerating apparatus a relay responsive to received signals, an escapement actuated thereby, a rotatable member releasable 10 for half a revolution at each actuation of said relay, two eccentrics relatively displaced 90 degrees on said rotatable member, a rotatable shaft having yielding driving engagement with said rotatable member motor means for rotating said shaft approximately in synchronism with received signals, a thermionic valve, means providing two different potentials, a switch device carried by said shaft arranged to close alternate contacts during successive half revolutions to 20 render said potentials alternately available for application to the grid circuit of said valve, switch means operatively connected with one of said eccentrics for intermittently closing said circuit, relay means responsive to change of anode current of said valve, a speed governor for said

motor means responsive to said relay means to change the limiting speed of said motor means above or below the synchronous speed. A second thermionic valve a second switch device carried by the shaft and arranged to close during a short interval of each rotation of said shaft corresponding approximately to the middle of each signal period, switch means operatively connected with the other of said eccentrics for reversing the polarity of potential applied to the grid circuit of said second thermionic valve, and signal relay means responsive to changes of anode current of said second thermionic valve. 80 85

13. In a telegraph system, a rotating shaft, switch means on said shaft for selecting one at a time, each one of a plurality of cyclically selectable potentials, other switch means responsive to received signals to charge the grid of a thermionic valve in accordance with the selected potential, and speed controlling means responsive to the change of anode current consequent upon the charging of said grid for maintaining the shaft rotating in synchronism with received signals. 90 95
